COMPOSITION APPLICATOR

William Wanner, Wilmette, Ill., assignor to
Sam'l Bingham's Son Mfg. Co., Chicago, Ill.,
a corporation of Illinois

Application May 2, 1938, Serial No. 205,417

8 Claims. (Cl. 91—43)

This invention relates to improvements in composition applicators for roller coating machines.

In coating printers' rollers, a composition or coating material is applied thereto to provide new surface. Machines for coating printers' rollers are well known and generally comprise an applicator or pan which is moved longitudinally of a rotating roller and into which hot coating composition is constantly supplied during the coating operation. The composition generally congeals or hardens rapidly upon cooling and consequently it has been the general practice to provide a composition heater in conjunction with the machine through which the material which overflows from the pan or applicator is recirculated to restore it to a proper temperature and viscosity.

It has been found, in using applicators of the type heretofore generally employed that notwithstanding the fact that the hot composition has been continuously supplied to the applicator in quantities considerably in excess of that required in coating a roller in an attempt to obtain uniformity in the applied coat, there has been imperfect circulation of the composition within the applicator especially on the side of the roller remote from the intake, with the result that the non-circulating composition in the applicator becomes cooled and partially congealed and when portions of this less-fluid composition contacted and adhered to the roller surface, imperfections in the finished coating resulted.

It is an object of the present improvements to provide an improved applicator which prevents the entrapment or retention and thereby congelation of coating composition within the applicator and thus eliminates the cause of imperfect coatings above mentioned.

A more specific object of the invention is to provide a composition applicator having an overflow passage or outlet port in the side or end thereof remote from the composition intake whereby there is induced a cross current of composition which flows in a direction transversely of the roller or rollers being coated and thereby subjecting the coatable surfaces thereof to composition of uniform temperature and viscosity and precluding the objectionable partial congelation of the material within the applicator during a coating operation.

A further object of the invention is to provide an outlet or overflow port provided with an adjustable gate for controlling the rate of discharge of composition from said port.

Another object of the invention is to provide

an applicator which may be constructed for use in coating a single roller or for coating a plurality of rollers simultaneously, such as a pair of rollers, for example, whereby not only is the capacity of the machine increased but the coatings will be applied under substantially identical conditions of temperature and viscosity of the composition whereby more uniform results will be obtained, which is very desirable in instances where the rollers are to be employed in high grade or quality printing.

Another object of the invention is to provide an applicator for simultaneously coating a plurality of printers' rollers which is provided with means for controlling the level of the composition material therein for effecting the uniform coating of the rollers.

Other objects relate to various advantageous features of construction such as the provision of an overflow duct for directing the coating material from the outlet port to a desired point of discharge, all of which will be apparent from a consideration of the following specification and accompanying drawing, wherein:

Fig. 1 is a perspective view of a composition or coating material applicator embodying the present improvements;

Fig. 2 is a broken elevation thereof;

Fig. 3 is a sectional view taken on line 3—3 of Fig. 2 and showing in dotted lines the relative position of a roller to the applicator during the coating operation;

Fig. 4 is a broken elevation of an applicator adapted to coat two rollers simultaneously;

Fig. 5 is a broken sectional view taken on line 5—5 of Fig. 4; and

Fig. 6 is a perspective view of a detachable and adjustable gate adapted for controlling the flow of liquid through an outlet provided in the form of applicators illustrated in the preceding figures.

In coating rollers with composition material, the rollers are sometimes arranged in vertical position during the coating operation while other machines provide for the support of the rollers in inclined position. Applicators shown and described herein are adapted for use in machines of the latter type.

As shown in Fig. 1, the applicator which is generally indicated by the numeral 10 comprises a pan or receptacle which may be fabricated of sheet metal but preferably is formed by casting as of aluminum, for example. The applicator comprises opposite end walls 11 and 12, a bottom wall 13 and front and rear walls 14 and 15. One of the end walls, such as end wall 11, may be

provided with an intake passage 16 as shown in Fig. 5 into which may be inserted a tube 17 which is secured therein by a set screw 18, for example. Connected with the tube 17 is a flexible hose 5 (not shown) through which hot composition material is delivered to the applicator.

The front and rear walls 14 and 15 are provided with recesses 14a, 15a, respectively for accommodating a roller or rollers 19 to be coated as illustrated in Figs. 3 and 4, the roller being shown in dotted lines in Fig. 3. The forward wall 14 is provided with a rubber dam 20 held in place by a U-shaped metal member 21. The dam 20 extends inwardly of the recess in the wall 14 and is adapted to contact a lower portion of a roller 19 to prevent the flow of composition material downwardly of the inclined roller ahead of the applicator 10 as the latter moves downwardly in a direction parallel with the rotating roller during the coating operation.

In accordance with the general practice, the recess or recesses 15a enable surplus composition which is supplied to the applicator in excess of that required for merely coating the rollers to 25 overflow the rear wall for discharge into a trough, or the like (not shown) which is disposed beneath the roller or rollers, the trough returning the composition material to a reservoir or tank where it is reheated and recirculated to the applicator.

For the purpose of preventing the partial congelation of composition material within the application during a coating operation, the end wall 12 is provided with an overflow or outlet port 22. This port is located at such height that it enables the composition material delivered to the receptacle to rise therein to a level for effecting the coating of the roller and to overflow through the recess or recesses 15a of the rear wall 15.

It will be seen by reference to Figs. 2 and 3 that when the level of the composition in the receptacle is such as to contact the roller 19 and to flow through the recess 15a, some of the surplus will also flow through the outlet port 22. There will thus be created a current of composition material from the intake side to the outlet side thereof transversely of the roller being coated which will preclude sufficient cooling of the composition material in the applicator at the discharge side thereof during the coating operation as to cause it to partially congeal.

Due to the fact that applicators of the type heretofore employed have not been provided with discharge ports to create cross currents of hot composition material, under some conditions congelation or partial congelation of the material occurred in the applicator at the side of the roller remote from the intake end thereof with the result that portions of such partially congealed or less-fluid composition material not infrequently came into contact with and adhered to the surface of the roller and formed imperfections in the finished coat. By the provision of the outlet port for the material in the receptacle at the side of the roller remote from the intake opening, this partial congelation is avoided due to the fact that a cross current of hot composition is created which flows transversely of the roller and maintains the entire body of material in the applicator at a temperature above the congelation point. With the present improvements, higher percentages of perfect coating operations have been obtained than with applicators of the prior type above mentioned.

As shown in Figs. 1, 2 and 3, the outlet port 22 communicates with a discharge passage 23 which is formed by an extension 24 of the applicator. The passage 23, as shown, extends downwardly and inwardly of the applicator and terminates in a discharge orifice 25 located beneath the applicator for returning to the trough (above referred to) the composition material which flows through the outlet port 22. The discharge of a portion of the composition material through the passage 23 along the wall 12 insulates the latter and assists in preventing excess cooling of the material in the end of the applicator remote from the intake thereof. The upper end of the passage 23 is open to the atmosphere to provide for the free flow of the composition from the port 23 downwardly and through the discharge orifice 25. The open end of the passage also facilitates the flushing out of any retained coating material after use of the apparatus.

It is desirable to provide means for controlling the flow of composition material through the outlet port 22 for varying the level of the composition within the applicator. Such control means may be in the form of a sheet metal gate 26 shown in perspective in Fig. 6. The gate illustrated is provided with an integral spring clip 27 adapted to engage the rear wall 15 with sufficient friction to retain the gate in any desired adjusted position. By lowering the gate from the position shown in Figs. 2 and 3, less composition material will be discharged through the port 22 and consequently the level of the material in the applicator may be regulated as required in obtaining most satisfactory coating results. Thus generally by raising the level of the composition in the applicator by lowering the gate 26, a thinner coating will be obtained and by raising the gate a thicker coating will be obtained. The gate preferably is so formed at the lower end as to preclude complete obstruction of the flow of composition through the outlet as shown in Fig. 6.

In Fig. 4 of the drawing, the applicator shown is constructed similarly to the form shown in the preceding figures except that it is of greater length and the front and rear walls are provided with recesses for accommodating two rollers. Since the construction of the applicator shown in Fig. 4 is practically identical to that shown in the preceding figures, the corresponding parts thereof have been given the same reference characters which have been primed for identification.

In using an applicator of the form shown in Fig. 4, it has been found desirable to support the applicator in a position inclined from the intake to the discharge end thereof, that is, from right to left as viewed in Fig. 4, for the purpose of further inducing a cross current of hot composition material transversely of the rollers. The rollers being coated simultaneously are therefore rotatably supported in different but parallel planes, the roller more remote from the intake end of the applicator being in the lower plane. The supporting means shown may comprise an inclined guide member indicated by numeral 28 in Fig. 4 which supports a carriage 29 which, by means of an adjustable bracket 30, supports either the single roller applicator 10 or the multiple roller applicator 10' at the desired inclination and carries the same longitudinally of the roller or rollers during the coating operation. The applicator may be adjusted vertically as may be necessary in accommodating the same to the roller or rollers being coated.

by means of a threaded adjusting member 31. A roller coating machine with which the present applicators are adapted for use is disclosed in a joint application, Serial No. 205,502, filed 5 May 2, 1938. The applicators herein shown and described may, of course, be employed with other types of mechanism for supporting and operating the same other than the mechanism shown in said joint application.

10 A gate 26 is shown in Fig. 4 by the vertical adjustment of which the rate of flow of composition from the applicator and consequently of the level of liquid in the applicator may be controlled as described above with reference to the 15 single roller applicator. In coating two or more rollers simultaneously with an applicator of the type shown in Fig. 4 which, as stated above, is inclined and the roller more remote from the intake is located in a plane lower than that of the 20 other roller, the level of the composition at the lower roller tends to rise relatively higher than the level at the intake end. For controlling the flow of composition from the first or higher coating section to the next lower coating section, 25 suitable flow control means may be employed such as the vertically adjustable gate 32. As shown in Fig. 4, this gate is disposed between the two roller coating sections of the applicator and is similar in construction to the gate 26 and 30 26. By raising or lowering the gates 26' and 32 the flow of composition from the applicator and from the higher roller coating section to the next coating section can be regulated for maintaining the level of the composition in the coating 35 sections of the applicator substantially uniform with reference to the respective rollers whereby more uniform results are obtained, that is, the coating applied to two or more rollers coated simultaneously will not vary in thickness due to 40 differences in the level of the composition in the coating sections of the applicator.

While I have shown and described certain embodiments of the improvements for the purpose of illustrating the principles thereof, I do not 45 wish to be restricted specifically thereto as various modifications within the spirit of the invention may be utilized.

What I claim as new and desire to cover by Letters Patent is:

50 1. A composition applicator for a roller coating machine comprising a receptacle provided with front and rear walls having recesses for accommodating a roller to be coated, an intake for fluid coating material at one side of said recesses, and an outlet at the opposite side of said recesses at a level adapted to induce the flow of coating material transversely of the roller.

55 2. A coating applicator for a roller coating machine comprising a receptacle having front and rear walls provided with recesses for accommodating a roller to be coated, an intake for fluid coating material at one end of the receptacle, an outlet at the opposite end of the receptacle at a level for inducing a flow of coating material transversely of the roller being coated, and adjustable means for controlling the flow of coating material through said outlet.

60 3. A coating applicator for a roller coating machine comprising a receptacle having front and

rear walls provided with recesses for accommodating a roller to be coated, an intake for fluid coating material at one end of the receptacle, an outlet at the opposite end of the receptacle at a level for inducing a flow of coating material transversely of the roller being coated, and adjustable means comprising a gate slidably attached to an adjacent wall of the receptacle for controlling the flow of coating material through said outlet.

65 4. A coating applicator for a roller coating machine comprising a receptacle having front and rear walls provided with recesses for accommodating a roller to be coated, end walls for said receptacle one provided with an intake for a fluid coating material and the other end having an outlet for inducing the flow of coating material transversely of the roller being coated, and an overflow duct communicating with said outlet for directing the material from said outlet to a 20 position of discharge.

70 5. A coating applicator for a roller coating machine comprising a receptacle having front and rear walls provided with recesses for accommodating a roller or rollers to be coated, end walls for said receptacle one provided with an intake for fluid coating material and the other end having an outlet for inducing the flow of material from one end of the receptacle to the other transversely of roller or rollers being coated, and an overflow duct communicating with said outlet and extending downwardly and under the receptacle for discharging the overflow 25 material therebeneath.

75 6. A coating applicator for roller coating machines comprising a receptacle having front and rear walls provided with recesses for accommodating one or more rollers to be coated, end walls for the receptacle one provided with an intake for fluid coating material and the other with an outlet for inducing the flow of material transversely of the roller or rollers being coated, and an overflow duct in said last mentioned end wall provided with open upper and lower ends and communicating with said outlet intermediate said open ends.

80 7. A coating applicator for roller coating machines comprising a receptacle having front and rear walls provided with recesses for accommodating a roller to be coated, an intake positioned at one side of said recess for supplying composition thereto in excess of that required for coating the roller, and composition outlet means positioned on the other side of said recess for controlling the level to which the composition material rises around the surface of a roller during a coating operation.

85 8. An applicator for a roller coating machine comprising a composition receptacle provided with recesses for accommodating one or more printers' rollers, inlet means for supplying composition to said receptacle during the coating operation, said receptacle having an outlet for composition material located at a side of the roller or rollers remote from said inlet, and adjustable means for varying the flow of material through said outlet for controlling the level of the composition material in the receptacle for varying the thickness of the applied coating.

90 WILLIAM WANNER. 70
